[57] CLAIM

The ornamental design for a combined doll and container, as shown and described.

DESCRIPTION

FIG. 1 is a perspective view of the combined doll and container according to the invention.

FIG. 2 is a front elevational view of the combined doll and container according to the invention.

FIG. 3 is a rear view of the combined doll and container.

FIG. 4 is a side view of the combined doll and container, the opposite side view being a mirror image except for the leaf adornment.

FIG. 5 is a bottom view of the combined doll and container.

FIG. 6 is a top view of the combined doll and container; and, FIG. 7 is a rear view of an alternate embodiment of the combined doll and container of FIG. 1, with a pocket.
